(57) **CLAIM**

The ornamental design for a television receiver, as shown and described.

DESCRIPTION

1. Television receiver

1.1 : Front perspective view

1.2 : Back perspective view

1.3 : Front

1.4 : Back

1.5 : Left

1.6 : Right

1.7 : Top

1.8 : Bottom

1.9 : Enlarged

1.10 : Enlarged

1.11 : Another view of 1.9 in an alternate configuration

1.12 : Another view of 1.9 in an alternate configuration

1.13 : Another view of 1.10 shown with the digital pen separated from the main body

The shading lines in reproduction 1.1 are used to show a portion of the display screen and do not represent its surface ornamentation; reproduction 1.9 is an enlarged view showing a camera of the middle upper part at the front side of the

(Continued)

main body; and reproduction 1.10 is an enlarged view showing a digital pen of the lower right part at the back side of the main body.

The dashed broken lines shown in the reproductions depict portions of the television receiver that form no part of the claimed design. The dot-dot-dashed broken line in reproductions 1.9-1.13 shows the boundary of the enlarged view and forms no part of the claimed design.

1 Claim, 13 Drawing Sheets
